UNITED STATES PATENT OFFICE.

ALLAN GLASSMAN, OF NEW YORK, N. Y.

BOUQUET HOLDER.

Application filed November 20, 1920. Serial No. 425,400.

To all whom it may concern:

Be it known that I, ALLAN GLASSMAN, a citizen of the United States, residing at New York city, in the county of New York and 5 State of New York, have invented certain new and useful Improvements in Bouquet Holders, of which the following is a specification.

This invention has relation to articles of 10 ornamentation, and has or an object to provide a device intended primarily to act as a fastening means for a bouquet of flowers or the like whereby the same may be secured to the apparel so that the bouquet, etc., may 15 be held in any position desired and in a secure manner.

Another object of the invention is to provide an article of ornamentation for the purpose above set forth consisting primarily of 20 the support having a penetrative or other means for securing the support to the apparel of the person, and combined therewith a fastening means of various designs and 25 form intended to receive the stem of a bouquet of flowers or the like whereby the bouquet may be held in any desired position and securely held against dislodgment.

In addition to the foregoing this invention comprehends improvements in the details of 30 construction and arrangement of parts to be hereinafter described and particularly set forth in the appended claims.

In the accompanying drawings in which similar and corresponding parts are designated by the same characters of reference 35 throughout the several views in which they appear,

Figure 1 is a view in perspective of a bouquet holder constructed in accordance 40 with my invention.

Figure 2 is a view thereof in top plan with parts broken away.

Figure 3 is a view in top plan with parts broken away with slightly different form 45 of the invention.

Figure 4 is another view in top plan with parts broken away to show details illustrating a still further modified form of the invention.

50 Figure 5 is a view in top plan partly in section illustrating a still further modified form and

Figure 6 is a view in perspective illustrating a form of the invention to be used as 55 a stick pin.

With reference to Figures 1 and 2 of the

drawing, 10 indicates a bar forming the base portion of the device and to the back of which is pivotally secured a pin fastening 11 designed to be held in place by means of the guard 12, all of which is of conventional type. The bar 10 may be gold plated, solid gold or ornamented in any manner desired, and secured to the front face thereof is a substantially circular member 13 which 60 however is cut away at its side to form the gap 14. The outer terminal of the member 13 is formed with a channel 15 extending for more than one-fourth of the entire circumference of the device whereby an arcuate 70 member 16 may be slidably held therein. A coil spring 17 inserted in said channel 15 bears at one end against the end of the bar 16 and the other end against the inner end of the channel to urge said member 16 outward. 75 The other terminal of the circular member 13 is recessed as at 18 to receive the projecting end of the member 16, thus defining a circular member designed to receive the stems of a bouquet of flowers. A pin 19 extending from the member 16 serves as a means for retrenching said member against the tension of the spring 17 to open the gap 14 so that the stems of the flowers may be 80 readily inserted therein.

In use the bar 10 is held to the apparel of a person by means of the fastening stem and the stems of the flowers inserted within the circular member 17 in the manner above set forth thus holding the bouquet securely 90 against dislodgment. It will be obvious that the bouquet may be held in either an upright, inverted or horizontal position as desired by merely adjusting the fastening device accordingly.

I have illustrated in Figure 3 a further modified form of the invention consisting of the bar 10^a having the circular member 13^a secured to the front face thereof, otherwise constructed exactly as in the form just described excepting that the gap 14^a is located forwardly of the device and not laterally as in the first case mentioned.

I have illustrated in Figure 4 a still further modified invention consisting of the 105 aligned members 20 defining the base portion of the device but having their adjacent ends in spaced relation. Formed with said adjacent ends is a substantially circular member 21 the same however being divided and its terminals formed with the adjacent ends of the members 20. One portion of the mem-

ber 21 is channeled to receive an arcuate bar 22 which is designed normally to bridge the gap between the adjacent ends of the member 20 and the terminals of the member 21.

5 A spring 23 inserted in said channel portion urges the bar 22 in this position but permits said bar to be moved into the channel of the member to open the gap at the rear of the device so that the stems of flowers 10 may be readily inserted therein. A pin fastening 24 of conventional type is mounted at the back of the member 20 whereby the device 15 may be readily secured to the apparel.

I have illustrated in Figure 5 a still further modified form of the invention consisting of the aligned members 25 having their adjacent ends in spaced relation and connected together by means of the substantially semi-elliptical bar 26 the terminals 20 of which are secured to the terminals of the member 25. One of the members 25 is formed with a channel 27 to receive a straight bar 28 which lies therein, the opposite member 25 being provided with a recess 29 to receive the opposite end of said bar 28. A coil spring 30 interposed in the above mentioned channel urges the bar outward to bridge the gap between the ends 25 of the members 25. The operation of the device is otherwise similar to that of the device last described. A pin fastening 31 of conventional type may be mounted upon the rear of the device to secure the same to the apparel.

35 I have illustrated in Figure 6 a still further modified form of my invention consisting of a substantially circular member 32 identically the same construction to the member 13 described in the first form and 40 in a similar manner having the sliding bar 16 bridging the gap between the terminals of said member. I provide a pin or other penetrative element 33 one end of which is secured to the periphery of the member 32 45 in such a position that the member 33 extends at right angles to the plane of the member 32 as shown. This device may be

secured as a stick pin and in any size to secure the stem of one or more flowers thus providing an efficient means for holding a 50 boutonnière or the like.

From the foregoing it will be seen that I have provided a novel form of fastening device which may be readily adjusted in any position to hold the bouquets of flowers 55 and which at the same time provides an ornamental device which does not detract in any manner from the appearance of the bouquet. Other uses and advantages will readily occur to those who become familiar 60 with the use of this device.

While I have illustrated and described my invention with some degree of particularity, I realize that in practice various alterations 65 therein may be made. I therefore reserve the right and privilege of changing the form of the details of construction or otherwise altering the arrangement of the correlated parts without departing from the spirit of the invention or the scope of the 70 appended claims.

Having thus described my invention what I claim as new and desire to secure by United States Letters Patent is:

1. A bouquet holder including a base portion, a circular element secured thereto having a gap therein, said circular element being channeled at one end, a movable element operating in said channel to close the gap, and a spring means for urging said movable element to a closed position. 75

2. A bouquet holder including a base portion, a substantially circular element secured thereto having one portion cut-away to form a gap and both terminals of said 80 cut-away portion channeled, an arcuate bar operating in one channel designed to be seated at its opposite end in the other channel, and a spring in the first mentioned channel urging said arcuate member to 85 closed position.

In testimony whereof I affix my signature.

ALLAN GLASSMAN.
